UNITED STATES PATENT OFFICE.

PAUL DOROZYNSKI, OF WINNIPEG, MANITOBA, CANADA.

PERMUTATION LOCK.

1,413,525.

Specification of Letters Patent. Patented Apr. 18, 1922.

Application filed April 28, 1921. Serial No. 465,332.

To all whom it may concern:

Be it known that I, PAUL DOROZYNSKI, a citizen of Ukraine, residing at Winnipeg, in the Province of Manitoba and Dominion of Canada, have invented certain new and useful Improvements in Permutation Locks, of which the following is a specification.

This invention relates to certain new and useful improvements in permutation locks and has particular reference to a lock capable of broad application but more especially designed for use as a box or trunk lock.

The primary object of the invention resides in the provision of a permutation lock wherein a plurality of independently operated notched disks are adapted to be rotatively positioned for alining the disk notches to permit the sliding movement of a latch keeper for freeing a latch therefrom.

20 A further object of the invention has reference to a permutation lock especially designed for boxes or trunks wherein a latch keeper is slidably supported by the base portion of a trunk and having depending arms associated with permutation controlled notched disks, the disks and arms cooperating to permit sliding movement of the latch keeper whereby a latch hook carried by the trunk cover may be disengaged therefrom.

30 With the above general objects in view and others that will appear as the nature of the invention is better understood, the invention consists in the novel form, combination and arrangement of parts hereinafter more 35 fully described and shown in the accompanying drawings, in which like reference characters indicate corresponding parts throughout the several views.

In the drawings,

40 Figure 1 is a fragmentary front elevational view of a portion of a box or trunk with the present type of permutation lock operatively arranged therein,

45 Figure 2 is a longitudinal sectional view taken on line II—II of Figure 1,

Figure 3 is a vertical longitudinal sectional view showing the permutation controlled notched disks and the latch keeper moved to its locked position,

50 Figure 4 is a longitudinal sectional view similar to Figure 3 showing the notched disks moved to a position to permit sliding movement of the latch keeper,

Figure 5 is a vertical cross sectional view 55 taken on line V—V of Figure 1 showing the

latch hook carried by the cover depending into the opening of the latch keeper carried by the base,

Figure 6 is a vertical cross sectional view taken on line VI—VI of Figure 1 showing the spring abutment arm for the sliding latch keeper and

Figure 7 is a perspective view of the latch keeper.

Referring more in detail to the accompanying drawings, there is illustrated a permutation lock, for purposes of illustration shown as applied to a trunk embodying a base portion 1 and a cover 2, the base portion 1 being provided with a casing section 3 to accommodate the permutation lock mechanism while a similar casing section 4 is carried by the cover 2 for cooperation with the casing section 3, and further carrying a latch hook.

75 The permutation lock mechanism includes a plurality of shafts 5 journaled transversely of the casing 3, each shaft having a disk 6 secured thereto within the casing 3 while the outer projecting end of each shaft carries a graduated plate 7 rotatable therewith while the shaft is operated by the terminal knob 8, the graduated plates 7 having characters thereon associated with the indicator marks 9 upon the front wall of the base section 1 85 as clearly shown in Figure 1. For purposes presently to appear, each disk 6 has a peripheral notch 10 formed therein.

A latch hook keeper of the type more clearly shown in Figures 3, 4, and 7 is slidably disposed within the casing 3 and embodies an elongated plate 11 having pairs of elongated slots 12 adjacent each end thereof through which slots retaining screws 13 are passed for securing the sliding keeper plate 11 to the upper wall of the casing 3 as shown in Figure 3 and 4. Depending arms 14 carried by the keeper plate 11 have inwardly directed feet 15 traversing the adjacent edge of a cooperating disk 6 as shown in Figure 100

5. One end of the plate 11 has a depending arm 16 provided with a stud 17 upon the outer face thereof for receiving one end of a coil spring 18, the other end of which engages the lower end of a cooperating arm 19 105 secured to and depending from the upper wall of the casing 3 as clearly shown in Figures 2, 3, 4, and 6, the spring tending to force the keeper plate 11 in one direction.

As shown in Figures 3, 4, and 5, a plate 110

20 is secured to the lower face of the upper casing 4 and carries a latch hook 21 depending through an opening 22 in the upper wall of the casing 3, and also through the keeper 5 opening 23 in the latch keeper plate 11, the spring 18 moving the plate 11 to its limit in one direction to cause one wall of the opening 23 to overlie the hooked end of the latch 21 as shown in Figure 3. The manual shifting 10 of the keeper plate 11 embodies the provision of slotted openings 24 in the side walls of the casing 3 with an operating arm 25 slidably positioned in said openings and having a head 26 for manipulation thereof, the operating arm 25 engaging the side of the depending arm 14 at the end of the keeper plate 11 opposite the arm 16. In the operation 15 of the device, assuming that the trunk is in the locked position as shown in Figure 3, the disks 6 are rotated by operating the shafts 5 to position the disk notches 10 in alignment with the angle feet 15 as shown in Figure 4, the permutation characters upon the plates 7 cooperating with the marks 9 20 determining the relative positions of the disk slots. When the disks are so positioned, as to aline the notches 10 with the angle feet 15, the operating arm 25 is shifted by gripping the head 26 to move the latch plate 11 25 against the tension of the spring 18, the angle feet 15 being received in the disk notches 10 and causing the plate 11 to be moved to a position whereby the latch hook 21 is capable of being freed from the plate 11. With 30 the disk notches alined with the feet 15, and with the trunk lid 2 in open position, the lid may be automatically moved to a closed and locked position by the beveled end of the keeper hook 21 engaging the adjacent wall 35 of the opening 23 to shift the plate against the spring tension thereon, but in opening the lock, it is necessary to shift the keeper plate by the operating arm 25, after having

aligned the disk notches 10 with the keeper feet 15.

45

While there is herein shown and described the preferred form of the invention, it is nevertheless to be understood that minor changes may be made without departing from the spirit and scope of the invention 50 as claimed.

What is claimed as new is:

A permutation lock of the type described comprising upper and lower body members, permutation lock mechanism including a 55 latch hook carried by the upper member, a sliding latch plate carried by the lower member, arms depending from said plate adjacent one longitudinal edge thereof and having the lower ends thereof bent inwardly 60 to form alined angle feet, an arm depending from one end of said plate, shafts journaled transversely of the lower member and alined with said feet, a disk fixed to each shaft and having a peripheral notch therein, 65 permutation plates carried by said shafts exteriorly of the lower member and adapted to be operated to cause the disk notches to register with the angle feet whereby the sliding latch plate may be moved to free the latch 70 hook from the latch plate, an arm depending from the lower member adjacent the end arm of the latch plate, a compression spring interposed between the two last named arms for holding the sliding latch plate at its limit 75 of movement in one direction, and a rod attached to the latch plate slidably extending through the lower member for shifting the latch plate against the spring tension thereon to disengage the side arms from the disks. 80
